UNITED STATES PATENT OFFICE.

OSCAR M. LEICH, OF ROCHESTER, NEW YORK, ASSIGNOR TO STROMBERG-CARLSON TELEPHONE MANUFACTURING COMPANY, OF ROCHESTER, NEW YORK, A CORPORATION OF NEW YORK.

SWITCHBOARD-SIGNAL.

No. 918,682.

Specification of Letters Patent.

Patented April 20, 1909.

Application filed July 29, 1907. Serial No. 386,001.

To all whom it may concern:

Be it known that I, OSCAR M. LEICH, a citizen of the United States, residing at Rochester, in the county of Monroe and State 5 of New York, have invented a new and Improved Switchboard - Signal, of which the following is a specification.

An object of my invention is to construct a combined operator's key and signaling device in such a manner that the operator in responding to a call indicated by the signaling device, upon moving a key used in conjunction with such signaling device will restore such device to its initial or concealed 15 position.

More specifically, my invention as disclosed by the accompanying drawings and specification, consists in a ringing and listening key and an operator's clearing out signal 20 as commonly used in connection with telephone switchboard cord circuits, such key and clearing out signal being so related mechanically as to constitute a single mechanism such that, after the signal has been actuated so as to show a proper display surface 25 or indicator to the operator, such signal may be restored to its concealed position by a movement of the key, in the case herein shown to its listening position.

Another object of my invention is to provide a convenient, cheap and effectual means for adjusting the magnetic effort required to release an indicator of this class.

The advantages resulting from my invention are numerous, some of the most prominent being the more intimate association of the apparatus used in the cord circuits of telephone switchboards and the simplification of the cabling and wiring necessary for 40 properly connecting the signals and keys to the remaining apparatus of the switchboard.

The several drawings illustrating my invention are as follows:

Figure 1 is a side view of my signal complete and shows the indicator in its engaged position. Fig. 2 is a view showing partially in vertical section, the co-operating parts between the cam of the operator's key and the indicator, as well as the construction of such indicator and means carried by the armature of the electromagnet for engaging the same. The parts are shown in this figure in the position they assume when the indicator is re-

stored to its concealed position by the operation of the cam of the operator's key. Fig. 3 is a view similar to Fig. 2 showing the indicator in its displayed position. Fig. 4 is a top view of the shield for the indicator and shows the apertures therein for disclosing such indicator when in its operated position. Fig. 5 shows a modified form of indicator. Fig. 6 is a top view of lever *k*.

Similar letters refer to similar parts throughout the several views.

Referring to the drawings, *a* is a mounting plate secured to the under side of which are seen brackets *d d'* which serve to support the bent bars *u* between which and insulated therefrom are supported the springs *i*, *j*, *j'* and *j''*. The springs *i* and *j* are engaged by rollers *h* pivoted to the operating cam *b*, which in turn is pivoted in the mounting plate *a* at *p* and is provided with an operating handle *c* for suitably actuating the contacts carried by the springs *i* and *j*. The cam *b* carries pins *g* and *j* for limiting the motion of such cam in either direction.

Since this invention is not concerned with the particular function performed by the springs *i* and *j*, the circuit conditions controlled by such springs are not herein described, but as shown in the drawings, these springs are designed to control the ringing and listening condition of a telephone cord circuit. The button *c'* adapted to operate vertically the cam *h* and thereby to actuate the springs *j'* and *j''*, is designed to control a ring back circuit in connection with the cord circuit above mentioned which, for the reason already indicated, is not herein described in detail. The bars *u*, besides supporting the springs just described, are attached to the electromagnet *t* which is also supported by the bracket *s* from the plate *a*. The electromagnet *t* is thus held in a vertical position and is provided with an armature *t'* pivoted at *p'* in the bracket *s*, such armature being counterbalanced by a weight *m* secured thereto by a bar or arm *n* of such material that it may be readily bent to give the desired balance of the armature *t'*, whereby the amount of tractive effort necessarily exerted by the winding *t* of the electromagnet *t* to draw the armature *t'* downward and therefore to move the weight *m* upward, may be varied as desired. The arm *n* should be of such material as to be readily bendable to

various positions to readily facilitate the adjustment just described and yet such arm should possess sufficient rigidity to remain in any particular adjustment given it. The 5 armature t^1 has folded about it as indicated, a non-magnetic strip of metal t^2 which serves to prevent the armature t^1 from sticking to the magnet t when attracted thereby. This non-magnetic strip t^2 extends between the 10 armature t^1 and the arm n and has formed therein as indicated, an opening from which the projecting tongue t^4 is pressed, such opening being adapted to engage the arm v^4 carried by the plate v^3 when the indicator is in 15 its concealed position. The plate v^3 is secured to a shutter v pivoted at p^3 in the plate a , such shutter having a rearwardly extending curved arm v^2 about which a thin indicator v^1 is secured as indicated. A shield r 20 secured to the upper surface of the plate a and having openings r^3 therein, is provided in order to protect the indicator and shutter from accidental injury. The openings r^3 are closed by a transparent screen r^1 held in 25 place by a curved strip r^2 similar in conformation to the inside surface of the shield r . From this it will be seen that the shield just described constitutes a perfect protection for the shutter and indicator while at the same 30 time permitting such indicator to be readily seen when the shutter is released from the armature by the attraction of the electromagnet, for which condition the action of gravity moves such shutter and indicator to 35 the position indicated in Fig. 3. In this position the arm v^4 engages a contact w supported and insulated from the under side of the plate a by a bracket w^1 as indicated, whereby any suitable night alarm or similar 40 circuit may be closed to call the operator's attention to the fact that the indicator and shutter have been released and that such indicator is in the displayed position. The bracket d^1 has formed thereon two curved 45 arms d^2 conformed to support at their outer ends the pivots p^1 of lever k , which lever is conformed at its left hand end to be engaged by the stop pin f carried by the cam b when the handle c is moved to the right, whereby 50 the right hand end of such lever k is brought into engagement with a suitable cam surface on the plate v^3 , as a result of which the indicator v^1 and shutter v are moved around to the right and the bar v^4 is brought into engagement with the opening above described 55 in the strip t^2 . The tongue t^4 serves to prevent the shutter v and indicator v^1 being moved too far around to the right. The pivots p^1 as shown in Fig. 6 are formed integrally with the lever k .

While I have in the drawings thus far described, indicated the shutter v and indicator v^1 as separate members, these two may be combined in one if desired, as indicated at v^6 in Fig. 5, by suitably proportioning the parts,

As a result of the construction above described it will be seen that when the electromagnet t is energized in any suitable manner not shown, and the armature t^1 is attracted thereby, the shutter v and indicator v^1 carried thereby are released and such indicator assumes a position behind the openings r^3 whereby the operator readily observes the same. It is preferable, though not necessary, to color or mark the outer surface of the indicator v^1 in contrast with the appearance of the parts through the openings r^3 when the shutter and indicator are in their normal or engaged position. 70

After the operator has observed the signal 80 presented as described above, the shutter and indicator may be moved to their engaged position either during the regular operation of the handle c or by a special movement of such handle to the right as the case may be. 85

In the specifications and drawings just described I have shown my invention as embodied in a standard ringing and listening key combined with a drop signal controlled by a vertical electromagnet. Obviously, 90 without departing from the spirit of my invention, I may make use of this key and signal for any other desired purpose in which it is desirable to effect circuit changes in response to a signal used to call for such 95 changes.

What I claim is:

1. In a switchboard signal, in combination with an operator's key, an electromagnet and an armature adapted to be attracted 100 thereby, an indicator adapted to occupy either a displayed or a concealed position, means carried by such armature for holding such indicator in a concealed position and means actuated by such operator's key for 105 moving such indicator from a displayed to a concealed position.

2. In a switchboard signal, in combination with an operator's key, a vertically disposed electromagnet and an armature adapted 110 to be attracted thereby, an indicator adapted to occupy either a displayed or a concealed position, means carried by such armature for holding such indicator in a concealed position and means actuated by such operator's key for moving such indicator from a displayed to a concealed position. 115

3. In a switchboard signal, in combination with an operator's key, a vertically disposed electromagnet and a horizontally disposed armature adapted to be attracted thereby, an indicator adapted to occupy either a displayed or a concealed position, means carried by such armature for holding such indicator in a concealed position and means actuated by such operator's key for 120 moving such indicator from a displayed to a concealed position. 125

4. In a switchboard signal, in combination with an operator's key, an electromag- 130

net and an armature adapted to be attracted thereby, an indicator adapted to occupy either a displayed or a concealed position, means carried by such armature for holding 5 such indicator in a concealed position, means actuated by such operator's key for moving such indicator from a displayed to a concealed position and means carried by the armature for varying the force required to 10 operate such armature.

5. In a switchboard signal, in combination with an operator's key, an electromagnet and an armature adapted to be attracted thereby, an indicator adapted to occupy either a displayed 15 or a concealed position, means carried by such armature for holding such indicator in a concealed position, means actuated by such operator's key for moving such indicator from a displayed to a concealed position and 20 a weight secured to such armature by a bendable arm for varying the force required to operate such armature.

6. In a switchboard signal, in combination with an operator's key, a vertically disposed 25 electromagnet and a horizontally disposed armature adapted to be attracted thereby, an indicator adapted to occupy either a displayed or a concealed position, means carried by such armature for holding such indicator 30 in a concealed position, means actuated by such operator's key for moving such indicator from a displayed to a concealed position and a weight secured to such armature by a bendable arm for varying the force required 35 to operate such armature.

7. In a telephone switchboard signal, in combination with a ringing and listening key, an electromagnet and an armature adapted to be attracted thereby, a drop shutter, an 40 indicator carried thereby and adapted to occupy either a displayed or a concealed position, means carried by such shutter for engaging such armature when such indicator is 45 in a concealed position and means operated by such ringing and listening key for moving such indicator from a displayed to a concealed position.

8. In a telephone switchboard signal, in combination with a ringing and listening key, 50 an electromagnet and an armature adapted to be attracted thereby, a drop shutter, an indicator carried thereby and adapted to occupy either a displayed or a concealed position, means carried by such shutter for engaging such armature when such indicator is 55 in a concealed position, means operated by such ringing and listening key for moving such indicator from a displayed to a concealed position and means carried by the 60 armature for varying the force required to operate such armature.

9. In a telephone switchboard signal, in combination with a ringing and listening key, a vertically disposed electromagnet and a 65 horizontally disposed armature adapted to be

attracted thereby, a drop shutter, an indicator carried thereby and adapted to occupy either a displayed or a concealed position, means carried by such shutter for engaging such armature when such indicator is in a concealed position, means operated by such ringing and listening key for moving such indicator from a displayed to a concealed position and a weight secured to such armature by a bendable arm for varying the force required 70 to operate such armature.

10. In a telephone switchboard signal, in combination with a ringing and listening key, an electromagnet and an armature adapted to be attracted thereby, a drop shutter, an indicator carried thereby and adapted to occupy either a displayed or a concealed position, means carried by such shutter for engaging such armature when such indicator is in a concealed position, a protecting shield 75 for such indicator, such shield serving to conceal such indicator when such shutter is in an engaged position and to disclose such indicator when such shutter is released and means operated by such ringing and listening 80 key for moving such indicator from a displayed to a concealed position.

11. In a telephone switchboard signal, in combination with a ringing and listening key, an electromagnet and an armature 85 adapted to be attracted thereby, a drop shutter, an indicator carried thereby and adapted to occupy either a displayed or a concealed position, means carried by such shutter for engaging such armature when 90 such indicator is in a concealed position, a protecting shield for such indicator, such shield serving to conceal such indicator when such shutter is in an engaged position and provided with an opening for disclosing such 95 indicator when such shutter is released and means operated by such ringing and listening key when moved to a listening position for moving such indicator from a displayed to a concealed position.

12. In a telephone switchboard signal, in combination with a ringing and listening key, an electromagnet and an armature adapted to be attracted thereby, a drop shutter, an indicator carried thereby and adapted to occupy either a displayed or a concealed position, means carried by such shutter for engaging such armature when such indicator is in a concealed position, a 100 protecting shield for such indicator, such shield serving to conceal such indicator when such shutter is in an engaged position and provided with an opening having a transparent screen therein for disclosing such indicator when such shutter is released and means operated by such ringing and listening 105 key when moved to a listening position for moving such indicator from a displayed to a concealed position.

13. In a telephone switchboard signal, in 110

115

120

125

combination with a ringing and listening key and the operating cam thereof, an electromagnet and an armature adapted to be attracted thereby, a drop shutter, an indicator carried thereby and adapted to occupy either a displayed or a concealed position, means carried by such shutter for engaging such armature when such indicator is in a concealed position and a lever for communicating motion from the operating cam of such ringing and listening key to such shutter for moving such indicator from a displayed to a concealed position.

14. In a telephone switchboard signal, in combination with a ringing and listening key and the operating cam thereof, an electromagnet and an armature adapted to be attracted thereby, a drop shutter, an indicator carried thereby and adapted to occupy either a displayed or a concealed position, means carried by such shutter for engaging such armature when such indicator is in a concealed position and a lever pivoted to the frame of such signal for communicating motion from the operating cam of such ringing

and listening key to such shutter for moving such indicator from a displayed to a concealed position.

15. In a telephone switchboard signal, in combination with a ringing and listening key and the operating cam thereof, an electromagnet and an armature adapted to be attracted thereby, a drop shutter, an indicator carried thereby and adapted to occupy either a displayed or a concealed position, means carried by such shutter for engaging such armature when such indicator is in a concealed position and a lever pivoted to the frame of such signal and adapted to coöperate at one end with a pin carried by such cam and at the other end with such shutter whereby when such cam is moved to a listening position such lever is operated to move such indicator from a displayed to a concealed position.

OSCAR M. LEICH.
